UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

ELECTRIC SHIP PROPULSION.

Application filed February 16, 1920. Serial No. 358,973.

To all whom it may concern:

Be it known that I, ERNST F. W. ALEXANDERSON, a citizen of the United States, residing at Schenectady, county of Schenectady, State of New York, have invented certain new and useful Improvements in Electric Ship Propulsion, of which the following is a specification.

My invention relates to electric propulsion and more particularly to electric ship propulsion.

An object of my invention is to provide a system of electric propulsion which will be reliable and efficient in operation and which will extend the advantages of electric propulsion to low speed boats such as cargo boats and the like.

A further object of my invention is to provide a system of electric ship propulsion particularly adapted for use with propeller driving motors adapted to operate as synchronous motors.

A further object of my invention is to provide methods of operating electric ship propulsion equipments which shall facilitate the use of propeller driving motors of the synchronous type and which shall make it possible, with such motors, to develop, simply and reliably, the high torque necessary for maneuvering purposes.

A further object of my invention is to provide control mechanism and connections which will facilitate the operation of ship propulsion systems, enabling difficult maneuvering operations to be carried out without the exercise of a high degree of skill on the part of the operator.

My invention will be better understood from the following description taken in connection with the accompanying drawings, and its scope will be pointed out in the appended claims.

The requirements that must be met in electric ship propulsion equipments of general utility are unfavorable to induction motor design because of the low propeller speeds encountered. Considerations of efficiency and economy usually require a high speed turbine driven generator, and even though a bipolar generator be used, the frequency of the generator output will frequently require a propeller motor having from 60 to 80 poles. An induction motor

designed to meet the conditions imposed will have a very low power factor or a dangerously small air gap, whereas the synchronous motor can be not only lighter but better in these respects. Difficulties lie in the way of using propeller driving motors of the synchronous type, however, for the reason that the synchronous motor characteristics are such that its starting and reversing torques are relatively small, even when the motor is provided with some well known form of squirrel cage winding. The requirements that a ship propulsion motor must fulfill, in order to be adapted to the characteristics of the propeller during the various maneuvering operations, have been determined experimentally. The results indicate that the momentum of the ship dragging the propeller through the water causes the propeller to be driven with considerable power by the water as a turbine, and that it cannot be stopped unless a torque nearly equal to the full load torque of the motor is exerted to break the propeller away from the water. This maximum torque occurs at a speed of about 35 per cent. After this point has been passed, the propeller can easily be stopped and can be held at stand-still by braking torque of only 40 per cent of the full-load torque. If a quick stopping of the ship is to be effected, it is not only necessary to stop the propeller, but it must be revolved in the opposite direction. Full-load motor torque in the reversed direction is required to revolve the propeller at 33 per cent speed backwards. In order to design a motor to meet the requirements for quick maneuvering and reversal of the propeller, it is obviously necessary to have a motor, which can not only deliver a considerable driving torque to the propeller when it rotates in the reversed direction, but which also has a braking effect as high as full-load driving torque in order to stop the propeller before it can be reversed.

According to my invention I use a propeller driving motor having synchronous motor characteristics and develop the torque necessary to break the propeller from the water and bring it approximately to stand-still by using the motor as an electric brake on the propeller. In order to make the propeller rotate in the opposite direc-

tion, I may proceed in a manner to take advantage of the peculiar characteristics of the combination of synchronous motor and synchronous generator which enable the motor and generator to stay together with continuity of torque characteristic from positive to negative rotation. According to this method of operation I am enabled to avoid the use of external rheostats or their equivalent in the form of high resistance windings and am enabled greatly to simplify the process of reversing the ship. My invention is not limited, however, to such method of reversing the propeller rotation, since it also includes the idea of securing such reversal, after the propeller has been substantially stopped, by operating the motor as an induction motor. According to this modification of the system and method of operation, the propeller driving motor is first operated as a synchronous generator to break the propeller from the water and bring it approximately to stand-still, then operated as an induction motor to reverse the propeller and bring it substantially to synchronism in the reversed direction, at which time synchronous operation is restored.

Referring to the accompanying drawings, Fig. 1 is a diagrammatic representation of a ship propulsion system comprising a turbine driven synchronous generator and a propeller driving motor of the synchronous type arranged for propeller reversal by synchronous motor action; Fig. 1^a is a sequence chart showing the preferred method of operating the system shown in Fig. 1; Fig. 2 is a diagrammatic representation of a modified form of ship propulsion system in which means are provided for holding the propeller at stand-still by short-circuiting connections; Fig. 2^a is a sequence chart corresponding to Fig. 2; Fig. 3 shows a modified form of ship propulsion system arranged for propeller reversal by induction motor action; Fig. 3^a is a sequence chart corresponding to Fig. 3; Fig. 4 shows a modified arrangement of circuit connections for performing the same operations as are performed in Fig. 3, the circuit connections being arranged for controller operation; Fig. 5 is a diagrammatic representation of a system comprising controller operated circuits for performing the operations of synchronous braking, induction motor reversal and synchronizing, together with relays insuring the proper operation of the various connecting devices; Fig. 6 is a diagrammatic representation of an entirely automatic system including means dependent upon the direction of propeller rotation for controlling the circuit connections; Fig. 7 is a diagrammatic representation of a modified arrangement of excitation circuits showing interlocking mechanism between the controller and steam levers; Figs. 8 and 9 are

details showing the operation of the stop for the steam lever; Fig. 10 is a diagrammatic representation of a system comprising two propeller driving motors supplied from a single generator with connections, whereby the motors may be interconnected for electric braking; Fig. 11 shows a modified form of system in which a plurality of generators and motors are used; Fig. 12 shows a system in which a plurality of motors are supplied from independent windings on the generator; Fig. 13 shows a modified form of ship propulsion system in which the idea of single phase braking is involved; and Figs. 14 and 15 represent a synchronous motor provided with double squirrel cage windings of a type particularly adapted for use in certain of the modifications of my invention.

Referring to Fig. 1, an elastic fluid turbine 1 is arranged to drive directly the revolving field member 2 of a synchronous generator whose stator 3 is adapted to be connected to the stator 4 of a propeller driving motor whose rotor 5 is directly connected to the propeller 6. Circuit controlling and reversing contactors 7, 8, 9, 10 and 11 are provided in the connections between the stator windings 3 and 4. With contactors 7, 8 and 10 closed, the phase rotation is such that the propeller is driven in one direction, and with contactors 7, 9 and 11 closed, the phase rotation is reversed to reverse the direction of propeller rotation. The propeller motor rotor is represented as a bipolar salient pole revolving field structure provided with an exciting winding 12 connected to slip rings 13 and 14. The rotor is provided with a squirrel cage winding 15 to enable the direction of rotation to be more readily reversed as hereinafter described. An exciter 16 is arranged to supply current in series to the exciting winding 12 of the motor and the exciting winding of the revolving field member 2 of the generator, which winding is connected to slip rings 17 and 18. An adjustable resistance 19 is shown in parallel with the field winding of the generator to indicate that the excitation current in the motor and generator field windings may be adjusted to independent values if desired. The exciter 16 is represented as provided with a field winding 16' excited from any convenient direct current source. Any suitable means for adjusting the field strength of the exciter is indicated by the adjustable resistance 19'. A switch 20 indicates a suitable means for interrupting the exciter field circuit to deenergize the field windings of the motor and generator. The turbine is represented as provided with a speed governing mechanism 21 for automatically maintaining any approximate speed which may be desired, whether the turbine is loaded or unloaded. A speed ad-

justing lever 22 is provided whereby the governing mechanism may be adjusted to hold any desired speed. This lever is intended to be arranged, in the modification shown in Fig. 1, to reduce the steam admission substantially to nothing when desired. The governing mechanism indicated in the drawing is of the type represented in the United States patent to Emmet, No. 1,137,308, dated April 27, 1915. It is to be understood, however, that my invention is not limited in any respect to any particular construction or type of governing mechanism for the turbine. Whatever type of governor is selected must be designed to hold the turbine at a very low speed, but as heretofore indicated, it is immaterial as far as my invention is concerned whether a centrifugal governor, a continuous flow geared oil pump type governor, or some other type of governor is used.

The operation of the modification shown in Fig. 1 will be readily understood from a description of the methods which I have devised for stopping and reversing the propeller. If it be assumed that the ship is proceeding at full speed ahead, the contactors 7, 8 and 10 will be closed. The exciter field switch 20 will be closed and the exciter 16 will be supplying current in series to the field winding 2 and 12 of the generator and motor. Normal excitation will thus be supplied to both generator and motor. The steam lever 22 will be opened to whatever position may be necessary to hold the desired speed, which position will depend upon the navigating conditions obtaining at the time. This phase of operation is indicated in Fig. 1^a by the legend FULL SPEED AHEAD. If it be now desired to reverse the ship the field circuits of generator and motor will first be deenergized, as for example, by opening exciter switch 20, lever 22 will be moved until the steam admission to the turbine is entirely shut off. Switches 7, 8 and 10 will be opened. Switches 7, 9 and 11 will then be closed thus reversing the phase rotation between generator and motor. It will be noted that the manipulation of the line contactors 7, 8, 9, 10 and 11 is thus performed while the circuits are dead with advantages well known in the art. Exciting current is now again supplied to the field windings of the generator and motor by closing the exciter switch 20. The condition that now obtains is represented in Fig. 1^a by the legend BRAKING.

The rotatable element 2 of the turbine is driven by the inertia of the moving parts of the generator and turbine, and the field element 5 of the motor is driven by the propeller 6 which is being dragged through the water by the momentum of the ship. The result is, therefore, that we have two genera-

tors short circuited upon each other with reversed phase rotation. A powerful synchronous braking torque is thus exerted upon the propeller 6 to break it away from the water and bring it to standstill. The braking energy developed in the motor is dissipated largely in the solid field cores of the generator rotating field element 2 by the eddy-currents therein developed. In addition to this energy dissipation, energy is dissipated in the motor and generator windings. An additional braking torque is superposed upon the synchronous braking torque by the induction motor action of the generator upon the squirrel cage winding 15 of the motor. It is obvious that the interchange of current between the two machines produces torque reactions which rapidly slow the two machines down approximately to standstill. The two machines will get into step automatically and the operator may start the reverse operation at his leisure by moving the lever 22 to put steam on the turbine again. I thus take advantage of the peculiar characteristics of the combination of synchronous motor and synchronous generator which enable the continuity of torque characteristic to be maintained from positive to negative rotation even though the turbine be brought to standstill during the operation.

The description of operation given in connection with the maneuvering operation which involves changing from full speed ahead to full speed astern is believed to make perfectly clear how other maneuvering operations are performed. It is apparent that acceleration of the ship from standstill will be accomplished by first, manipulating the contactor switches for the desired direction of operation, after which excitation will be applied to both motor and generator and steam gradually admitted to bring the machines up to speed synchronously. Similarly, if, when the ship is drifting ahead it be desired to accelerate to full speed ahead the turbine will be brought to a speed such that the generator and motor will be in substantial synchronism before the exciter switch 20 is closed. If, on the other hand, while the ship is drifting ahead, it be desired to reverse the motion of the ship the operation of synchronous braking will precede the operation of synchronous reversal.

In the arrangement heretofore described, the steam required to be admitted while the turbine is at or near standstill may involve such temperature changes as are injurious to steam turbines as at present constructed. This objection may be eliminated to a great extent by the arrangement shown in Fig. 2. In this arrangement, the generator is arranged to be connected to supply current to the propeller driving motor as in Fig. 1,

and the turbine is provided with a speed adjusting lever 22 as in Fig. 1. The arrangement differs from the arrangement shown in Fig. 1 by the provision of means for holding the motor at standstill by a short circuit across its terminals which is put on after the motor is stopped. This short circuiting means comprises normally open contactors 23 arranged to be closed by coils 24 arranged to be supplied from any convenient source, represented in the drawing as the source of excitation for the exciter field winding 16'. A switch 25 is provided in the circuit leading to coils 24. Switch 25 is arranged to be closed automatically when the propeller motor is at standstill. Contacts 26 are also provided in the circuit of coils 24 and these contacts are arranged to be closed when the lever 22 is in position to shut steam off from the turbine.

The operation of the modification shown in Fig. 2 in the maneuvering operation which consists in reversing the direction of the ship from full speed ahead to full speed astern is identical with the operation set forth in connection with Fig. 1 up to the point where the propeller reaches standstill. At this phase of the operation switch 25 is closed, and inasmuch as the steam lever 22 is in closed position at this phase of the operation, the circuit of coils 24 is closed at contacts 26, and the contactors 23 are, therefore, closed to establish a short circuit across the motor terminals. This short circuit holds the propeller motor at standstill and the operator can wait, without heating the turbine, until the ship has reached a speed at which reversal will take place as soon as he opens the steam lever. As soon as this speed has been reached, the operator will move the lever 22 to readmit steam to the turbine to effect synchronous reversal of the propeller in the manner set forth in connection with Fig. 1. The movement of the steam lever 22 at once interrupts the circuit of coils 24 to release the contactors 23, which interrupt the short circuit across the motor terminals. It will be observed that the switch 25 and contacts 26 are interlocked in such a way that the short circuit for holding the propeller at standstill will be established only when the motor is at standstill and the steam is off. It will also be apparent that the contactors 23 may be operated in the manner described without excessive arcing, even though the generator and motor field circuits remain closed, for the reason that the generator speed is very low when the short circuit is made and broken.

The feature of synchronous reversal and the idea of means for holding the propeller at a standstill are claimed in my divisional application Serial No. 500,024, filed September 12, 1921, for electric ship propulsion, assigned to the assignee of this application.

In the modifications shown in Figs. 1 and 2, I have shown the exciter connected to supply the generator and motor field windings in series, but it will be apparent that my invention is not limited to any particular arrangement of connections for the excitation circuits.

The modification shown in Fig. 3 differs from the modifications heretofore described in that provision is made for operating the propeller driving motor as an induction motor to reverse the direction of propeller rotation. The generator and motor construction, and the connections between the generator and motor stators 3 and 4, are identical with the corresponding features shown in Fig. 1. The turbine governing and speed mechanism is also identical with that of Fig. 1. The exciter 16 is, however, connected so that it can not only supply the generator and motor field windings in series, but also, so that its full capacity and voltage may be applied to either field winding separately, whereby over-excitation may be produced on either the generator or the motor. In this modification of my invention I prefer to use an exciter of considerably greater capacity than that necessary for normal operation, in order that, for a short interval of time, over-excitation may be simultaneously applied to both motor and generator field windings. A switch 27 is arranged to complete a circuit connecting the exciter 16 to supply the field windings 12 and 2 in series. A switch 28 is arranged to connect the motor field winding 12 directly across the terminals of the exciter 16. A resistor 29 is provided in this circuit for a purpose hereinafter described. A switch 30 is arranged to connect the exciter 16 directly across the terminals of the generator field winding 2. A switch 31 is arranged to short circuit the resistor 29.

The operation of the arrangement shown in Fig. 3 is as follows:

During full speed ahead contactors 7, 8 and 10 will be closed and switch 27 will be closed to connect the generator and motor field windings in series, as set forth in connection with the modification shown in Fig. 1, and this phase of operation is indicated by the legend FULL SPEED AHEAD in the sequence chart shown in Fig. 3a. If now it be desired to reverse the ship the switch 27 is opened to deenergize the motor and generator field windings, after which the line contactors 7, 8 and 10 are opened and contactors 7, 9 and 11 closed to reverse the phase rotation. During these operations the steam lever 22 will preferably have been moved to a position in which the speed of the turbine is reduced to about 25 per cent of its normal value. The switches 28 and 31 are now closed to apply the full voltage of the exciter to the motor field winding 12,

whereby approximately double excitation is applied to the motor while the generator field winding remains unexcited. A strong braking torque is, therefore, developed to break the propeller from the water and bring it approximately to standstill, the energy developed being dissipated in the generator field structure and in the generator and motor windings, as set forth in connection with Fig. 1. When the propeller has been stopped, or nearly stopped, switch 30 is closed to apply over-excitation to the generator field winding. When the generator field current has had time to build up, the switches 31 and 28 are opened to disconnect the motor field winding 12 from the exciter 16. The system is now arranged to function with strong induction motor torque to reverse the propeller, since the generator is over-excited and the motor field winding 12 deenergized. The reversing torque is produced in the squirrel cage winding 15 of the motor. As hereinafter indicated, a double squirrel cage winding may be used if desired. When the induction motor action has brought the propeller substantially to synchronous speed in the reversed direction, the switch 27 is closed and the switch 30 opened to connect the motor and generator field windings in series, which action brings the motor into exact synchronism with the generator, after which the lever 22 is adjusted to bring the ship to the desired speed in the reversed direction. The various operations performed in reversing the ship, which operations have just been described, are indicated in the sequence chart Fig. 8^a. In view of the preceding description the steps necessary for performing other maneuvering operations will be obvious.

Fig. 4 shows a modified arrangement of excitation circuits in a system arranged to perform the operations of synchronous braking, induction motor reversal and normal synchronous running, as in the modification shown in Fig. 3. In this modification I have shown a controller 32 arranged to control the operation of the various switches in the line and excitation circuits. It is obvious that a controller may be similarly arranged to control the circuits in the modifications heretofore described, but no such controller has been shown for the reason that I wish to emphasize the fact that my invention is not limited to any particular means for controlling the circuit connections, since these connections may, if desired, be made by switches arranged for direct manual operation. I have shown the controller with a row of contact fingers *a*, *b*, *c*, *d*, *e*, *f*, *g* and *h*, conventionally represented as stationary. Movable segments 33 and 34 are arranged to cooperate with the contact fingers to produce ahead and astern operation of the ship respectively.

The connections and operation of the modification shown in Fig. 4 will be most readily understood by considering the operation of the system in passing from full speed ahead to full speed astern. With the controller segment 33 moved to FULL SPEED position, fingers *a*, *c* and *e* of the controller will be energized, these contacts being connected by segment 33 to controller finger *b* which is connected to any convenient source of power. Fingers *a* and *c* maintain contactors 7, 8 and 10 in closed position, while finger *e* maintains switch 20 closed to energize the field winding 16' of the exciter 16. Switches 35, 36 and 37 are in the open position for the reason that their operating coils are deenergized. The exciter 16 is thus connected to energize field windings 2 and 12 in series. Normal excitation is thus supplied to both generator and motor and the system operates synchronously. It will be understood that in all arrangements in which the field windings are connected in series, means may be provided for independently adjusting the generator and motor field energization if desired. Assume that it is now desired quickly to reverse the ship. The steam lever 22 will be moved to the reduced speed or maneuvering position and the controller 32 thrown from AHEAD to ASTERN position. When the controller goes through off position all switches in the system will drop out. Controller segment 34 will then energize contact fingers *c* and *d* to close contactors 7, 9 and 11 to reverse the phase rotation between generator and motor. Controller segment 34 will next energize contact fingers *e* and *f* to close switches 20 and 35. The full capacity of the exciter 16 will now be impressed upon the motor field winding 12 for the reason that the generator field winding 2 will be short-circuited by the switch 35. Strong synchronous braking torque will, therefore, be developed in the motor to bring it approximately to standstill. The controller segment 32 will then be moved to deenergize contact finger *f* and energize contact finger *g*. Switch 35 will, therefore, be opened and switch 36 closed immediately thereafter. The full voltage and capacity of the exciter 16 will now be applied to the generator field winding 2, since the motor field winding 12 will be short circuited by switch 36. Strong induction motor torque is, therefore, exerted to reverse the propeller and accelerate it in the astern direction. When steady conditions have been reached controller segment 32 will be further moved to energize contact finger *h* to close switch 37 and deenergize contact finger *g* to open switch 36. Resistance 38 is now connected in parallel with field winding 12 and this winding is energized to bring the propeller driving motor into exact synchronism with the generator.

ator. The controller segment 34 may now be operated to full speed position deenergizing finger *h* to open switch 37 to connect field windings 2 and 12 in series for normal synchronous operation. The controller diagram indicates that the speed of the turbine is to be reduced while the controller is being operated to change the connections to produce maneuvering operations. It will be understood, however, that after connections for normal synchronous operation have been established, the steam lever 22 may be adjusted to hold the ship at any desired speed. While the excitation circuit connections of Fig. 4 permit of a somewhat simpler method of operation than the connections of Fig. 3, it will be observed that the arrangement of Fig. 3 is preferable for the reason that the generator and motor excitation circuits may be independently controlled, while with the arrangement shown in Fig. 4, the excitation of one machine must be reduced when the exciting winding of the other is simultaneously energized.

The modification shown in Fig. 5 is arranged to provide the same excitation circuit connections as the arrangement shown in Fig. 3. The system is arranged for remote control by means of a controller 32' provided with segments 33' and 34' cooperating with contact fingers *a*, *b*, *c*, *d*, *i*, *j* and *k*. The switches 27', 28', 30' and 31' and the resistance 29' correspond to the parts numbered 28 to 31 of Fig. 3. Relays are provided for insuring that the transition from synchronous braking to induction motor operation, and from induction motor operation to synchronous motor operation takes place only when conditions in the system are such as to determine the fact that the system may function properly when the changed connections are established. Interlocks are also provided for certain of the switches for controlling the excitation circuits arranged to insure that proper time intervals are provided to enable the current in the generator and motor field windings to build up in order that the switching operations may be performed without danger of the generator and motor falling out of step. For normal synchronous operation in the ahead direction, segment 33' of the controller energizes contact fingers *a* and *c* to close contactors 7, 8 and 10 as in Fig. 1. Finger *i* is energized to maintain switch 20 closed to render the exciter active. Switch 27' is held closed in a manner hereinafter set forth, and the generator and motor field windings 2 and 12 are thereby connected in series to the exciter 16 as in Fig. 3. Resistors 39 are provided in the connections between the generator and motor stator windings 3 and 4 to improve the power factor during synchronous braking. During normal synchronous operation these resistors are short circuited by contactors 40, the operating coils of which are energized from controller finger *j*. Normal synchronous operation, therefore, occurs precisely as in the modification shown in Fig. 3. While the governing and speed adjusting mechanism for the turbine is not illustrated in Fig. 5, it is to be understood that such mechanism is employed. The controller segments 33' and 34' are arranged to be moved by handle 41 and a member 42 is arranged to move with the controller handle. Member 42 is provided with projections 43 to engage a pin 44 located so as to stop the controller in the position to establish braking connections, as hereinafter set forth. The member 42 is adapted to be moved to a position where the pin 44 will not be engaged, by a lever 45 provided on the controller handle. The member 42 may also be moved to disengaged position by coil 46. The member 42 is, however, normally held by the spring 47 in such position that the means 43 will engage the pin 44. A relay 48 is arranged to operate a contact 49 in circuit with coil 46. Relay 48 is provided with a winding 50 in the form of a small direct current motor armature and this winding is supplied from any convenient source of direct current. The relay field winding 51 is arranged to be connected in one of the leads connecting the generator and motor stator windings 3 and 4. During synchronous braking, winding 51 is energized with alternating current. Relay 48 is provided with a pendulum comprising an adjustable weight 52 which maintains the contact 49 in open position when the winding 51 is unexcited. The relay is adjusted to have a natural period of one second. This relay will, therefore, remain open on a dead circuit and on high frequencies, but will close contact 49 intermittently on frequencies of about one cycle. A relay 53, similar in construction to relay 48, is arranged to control a contact 54 provided for a purpose hereinafter set forth. Winding 55 of relay 53 is connected across the terminals of motor field winding 12 through slip rings 13 and 14. A contact 28^a, interlocked with contact 28', is provided in the circuit of winding 55 for a purpose hereinafter described. Field winding 56 of relay 53 is arranged to be connected to any suitable direct current source. Relay 53 is provided with an adjustable weight 57 arranged to hold the contact 54 normally in open position. During induction motor operation a frequency corresponding to the frequency of slip is induced in the motor field winding 12, as will be obvious to those skilled in the art, and an alternating current having the frequency of slip is thus impressed upon the winding 55 while the generator is supplying current to the motor.

- for induction motor operation. This relay is adjusted to have a natural period of one-third second, that is, the pendulum makes three double swings per second. It is apparent that when the slip is greater than three cycles per second the contact 54 remains in the open position. The relay closes intermittently for frequencies of about three cycles, but is arranged to remain open
- 10 when direct current passes through the winding 55, which happens whenever the motor field winding is excited and the switch 28' opened. This condition of operation obtains when switch 27' is closed to
- 15 excite the generator and motor field windings in series. Switch 27' has mechanically connected therewith two interlock contacts 27^a and 27^b. Contact 27^a is arranged in the circuit of the coil controlling switch 28' and
- 20 contact 27^b is arranged in circuit with the coil controlling switch 30'. Switch 30' is provided with interlock contacts 30^a and 30^b. Contact 30^a is arranged in the circuit of the operating coil of switch 31'. The
- 25 functions of contact 30^b will be hereinafter set forth. Contact 30^b is arranged to have a delayed opening, the period of delay depending upon the time constant of the motor field winding 12. Contact 54 of relay
- 30 53 is arranged to complete a circuit from controller finger *b* to coil 58 arranged to close contacts 58^a, 58^b and 58^c. Contact 58^a is arranged to close a holding circuit for coil 58. The function of contact 58^b will be
- 35 hereinafter set forth. Contact 58^c is arranged to control the circuit of the operating coil for switch 27' and this contact is arranged to have a delayed closing, the period of delay depending upon the time constant of the generator field winding 2.
- 40 A switch 59 is arranged in parallel with contact 54 to enable the circuit of coil 58 to be closed manually whenever desired.
- As is the case with the modifications here-
- 45 tofore described, the operation of the arrangement shown in Fig. 5 may be most readily developed by considering the maneuvering operation which consists in changing from full speed ahead to full speed astern.
- 50 The connections established when controller segment 33' is moved to the FULL SPEED AHEAD position have been set forth in the preceding description of this modification. As the controller is moved through off-position
- 55 all of the switches and contactors fall out deenergizing all circuits. The controller segment 34' energizes controller fingers *c* and *d* to close contactors 7, 9 and 11 for reversed phase rotation. Controller finger *i* is next
- 60 energized to close switch 20 to render the exciter 16 active. Pin 44 engages projection 43 of member 42 to stop the controller in this position, which is the braking position, as will be evident from the fact that
- 65 controller finger *i* completes a circuit through interlocks 30^a and 27^a to the operating coil of switch 28'. Switch 28', therefore, closes to throw the full capacity of exciter 16 upon the field winding of the motor for strong synchronous braking. A circuit is also completed from controller finger *i* through interlock contact 30^a to close switch 31' and short circuit the resistance 29'. The braking currents circulating in the connections between stator windings 3 and 4 are arranged in this modification to traverse resistors 39. These resistors are shown for the purpose of indicating how the power factor of the braking circuit may be improved if desired. The circulating braking currents obviously decrease in frequency as the propeller slows down and the frequency in coil 51 correspondingly decreases. As heretofore set forth, the construction of relay 48 is such that the contact 49 remains open until the frequency of the braking currents is reduced to about one cycle per second. When this low frequency is reached the propeller will have been brought approximately to standstill and the contact 49 closes a circuit from controller finger *i* to coil 46 to move member 42, so that pin 44 no longer prevents movement of the controller handle 41. Further movement of controller segment 34' energizes controller finger *j* to establish a circuit for the operating coils of contactors 40, which thereupon short circuit the resistors 39. One of these contactors also short circuits the coil 51 of the relay 48 which thereupon ceases its intermittent operation and contact 49 remains open as heretofore described. Controller finger *j* also completes a circuit through interlock contact 27^b to the operating coil of switch 30'. Switch 30', therefore, closes and applies the full voltage of the exciter 16 to the field winding 2 of the generator. At this instant over-excitation is supplied both to the motor and generator field windings, thus throwing an excessive load on exciter 16. This load is of short duration, however, for the reason that interlock contact 30^b opens after an interval long enough to permit the current in the generator field winding to rise to full value, and the opening of contact 30^b causes switch 28' to open and deenergize the motor field winding 12. By thus delaying the change in the circuit of motor field winding 12 until after the generator field winding 2 has built up, I avoid the danger of the propeller slipping away during the time that it takes the current to build up in the generator field winding. It is obvious, however, that my invention is not limited to any particular way of securing this time interval between changes in the field circuit connections, since my invention covers broadly the idea of providing a means for performing this function in the combination, and it is immaterial whether the de-

lay is caused by some means directly or indirectly dependent upon the value of the generator field current or by the more practical means herein disclosed. From the preceding description, it is now obvious that the strongly excited generator supplies current to drive the propeller motor as an induction motor with strong reversing and accelerating torque. When switch 28' opened, interlock contact 28^a closed the circuit of winding 55 of relay 53. Winding 55 is, therefore, now subjected to the frequency induced in the motor field winding 12 by the currents circulating in the stator winding 4. As heretofore indicated, this frequency corresponds to the frequency of slip of the propeller driving motor which is now operating as an induction motor. As heretofore indicated, contact 54 of relay 53 remains open until the frequency of slip falls to about three cycles at which time this contact begins to close intermittently. If the controller has been moved to the FULL SPEED ASTERN position, the first closure of contact 54 completes a circuit from controller finger $\frac{1}{2}$ to coil 58 which is arranged to operate contacts 58^a, 58^b, and 58^c. Contacts 58^a and 58^b close immediately, the former completing a holding circuit independent of contact 54, for coil 58. Contact 58^c completes a circuit through interlock contact 27^a to close switch 28'. The closure of switch 28' energizes field winding 12 of the motor to bring it into synchronism with the generator. After an interval of time sufficient for the motor field current to be established, contact 58^c closes to energize the closing coil of switch 27'. At the instant switch 27' closes, interlock contact 27^a opens switch 28' and interlock contact 27^b opens switch 30'. During a small interval of time switches 27', 28' and 30' are closed and the resistance 29' is, therefore, provided for the purpose of preventing a short circuit on the exciter 16, which circuit would lead from one terminal of the exciter through switches 30', 27' and 28' to the other terminal of the exciter. Normal synchronous operating connections are now established for operation in the astern direction, the field windings 2 and 12 being connected in series through switch 27'.

The function of contact 28^a in the circuit of winding 55 of relay 53 of Fig. 5, will now be described. If winding 55 were connected directly to the terminals of field winding 12, and the relay arranged to hold contact 54 open with a direct electromotive force applied to its terminals, it is apparent that a kick would be produced tending to close the contact whenever the circuit of field winding 12 is interrupted. With such an arrangement, upon the opening of switch 28' at the completion of synchronous braking, contact 54 would energize coil 58, which

would thereafter be held closed by contact 58^a. Contact 58^b would immediately reclose switch 28' to restore the direct current excitation to the motor field winding, although the slip would be high and the motor so near standstill that it could not get into step with the generator. A moment later the contact 58^c would close switch 27' and open switches 28' and 30', establishing a circuit connecting the two field windings in series for normal synchronous operation, although it would be impossible for the motor to get into step with the generator. To prevent this undesirable operation, contact 28^a is arranged to complete the circuit of winding 55 only while switch 28' is in the open position. Winding 55 does not, therefore, experience the kick due to opening the motor field circuit at switch 28'.

While I have described the relays 48 and 53 as adjusted to effect the closing of their contacts at frequencies of one cycle and three cycles per second respectively, it is obvious that my invention is not limited to any particular frequency of operation. It is merely essential that contact be made only when the condition of the system determines that the system may function properly after the transition is made from one phase of operation to the next. It is, moreover, apparent that my invention is not limited to the particular means disclosed for controlling the transition from one phase of operation to the next, since frequency responsive relays of other types may be substituted. It is further apparent that my invention is not even limited to frequency responsive devices of any character for controlling the transition operations, since broadly considered, my invention contemplates the provision of means responsive to any condition which will determine that the system will operate properly with the changed connections which are to be established.

The mechanism for normally stopping the controller in the braking position is provided to insure against the operator of the system involuntarily performing a maneuvering operation which requires synchronous braking without pausing on the braking position of the controller. It is apparent, however, that for certain maneuvering operations synchronous braking is not necessary or desired. If, for example, the ship be drifting ahead and it be desired to change to full-speed-ahead, it is obviously not desirable to go through the synchronous braking phase of operation which would first bring the ship to a standstill. In order to enable this operation to be performed without synchronous braking, the lever 45 is provided. By gripping this lever with the controller handle, the operator may pass through the braking position without paus-

ing long enough to establish braking connections. It is apparent that my invention is not limited to any particular means for performing the function of eliminating the synchronous braking phase of operation.

It is apparent that synchronous braking is desired whenever the ship is to be brought quickly to a stop, even though it be not desired to move astern. Such quick stopping will be performed by throwing the controller to reverse position for synchronous braking and then to off position exactly as the corresponding operations are performed for ship propulsion systems operated by steam engines. This method of operation is, of course, contemplated in all of the modifications hereinbefore described.

Fig. 6 represents an entirely automatic ship propulsion system arranged for remote control. All maneuvering operations may be performed by mere manipulation of the controller to accomplish the desired maneuvering; synchronous braking, induction motor reversal, and synchronizing being automatically performed when necessary and at the proper time. The various connections established and the relays are practically the same as in the arrangement shown in Fig. 5, the principal difference being that a direction relay 60 is provided for eliminating the operation of synchronous braking when it is unnecessary and undesirable. The direction relay 60 comprises a disc 61 on the motor shaft arranged to operate the pivoted lever 62 in one direction or another according to its direction of rotation. The lever 62 is arranged to operate contacts 63 and 64 which are arranged to complete circuits leading from controller fingers *o* and *l* respectively. As shown in the drawing, the disc 61 is arranged to rotate counterclockwise when the propeller is running forwards and to run clockwise when the propeller is running backwards. Forward rotation closes contact 63 and backward rotation closes contact 64. Relay 48' differs from relay 48 of Fig. 5 in that the contact 49' is arranged to be normally closed instead of normally opened. This is accomplished by arranging coil 65 in series with coil 51 and arranging this coil so as to tend to hold the contact 49' open. The arrangement is such that with frequencies above those at which it is safe to change the connections from synchronous braking to induction motor operation, the contact 49' will be held open. At the predetermined frequency contact 49' closes.

The operation of the arrangement shown in Fig. 6 is as follows:

During full-speed-ahead the controller segment 33" maintains switches 7, 8 and 10 closed as in the modification shown in Fig. 5. The contact 63 of the direction relay will be closed. The switch 27' will be in closed po-

sition to excite the motor and generator field windings in series, as in Fig. 2. To reverse the ship, it is merely necessary to throw the controller from FULL SPEED AHEAD position to FULL SPEED ASTERN position. As the controller goes through off position, the line contactors and excitation controlling switches drop out, as in Fig. 5. The ASTERN segment 34" first energizes controller fingers *c* and *d* to close contactors 7, 9 and 11 for reversed phase rotation. No circuit is completed at controller finger *l* for the reason that contact 64 is open. Controller finger *m* is energized to close switches 20, 28' and 31', as in Fig. 5. Over-excitation is thus applied to the motor for synchronous braking. When the frequency of the braking currents falls to the predetermined value, relay 48' closes contact 49' and completes a circuit from controller finger *n* to close contactors 40 to short circuit resistors 39. One of the contactors 40 is provided with an interlock contact 40^a which completes a circuit from controller finger *m* through interlock contact 27^b to the operating coil of switch 30'. Switch 30', therefore, closes and applies over-excitation to the generator field winding 2. Switch 31' opens immediately and switch 28' opens after the interval determined by contact 30^b, as in Fig. 5. The opening of switch 28' de-energizes the motor field and interlock 28^a connects winding 55 of relay 53 across the terminals of the exciter field winding, as in Fig. 5. Induction motor reversal of the propeller now takes place and upon this reversal the direction relay closes contact 64 and opens contact 63. Contact 64 is, however, at this time in parallel with contact 49', which is closed, and the closing of contact 64, therefore, has no effect. The opening of contact 63 has no effect for the reason that controller finger *o* is unenergized at this time. When the slip of the motor has been reduced to the predetermined value, relay 53 closes contact 54 to establish synchronous motor operation connections exactly as in Fig. 5.

To explain the operation of the direction relay, assume now that, while the ship is moving full-speed astern, that the controller be thrown to OFF position permitting the ship to drift astern. While the ship is drifting, assume that it be desired to change to full-speed astern. The operator will merely throw the controller to ASTERN position. Controller fingers *c* and *d* will close contactors 7, 9 and 11 for astern operation, and controller finger *l* will complete a circuit through contact 64 of the direction relay, which is now closed, directly to the operating coils of contactors 40. It will be observed that this circuit shunts the contact 49' of the relay 48', and that connections are, therefore, at once established, which would not otherwise be established until the

contact 49' closed. Interlock contact 40^a is, therefore, at once closed to close switch 30' for induction motor operation, and the operation of synchronous braking is thus eliminated. It is believed that other maneuvering operations will be obvious from the maneuvering operations described.

10 The combination of a ship propulsion system involving a direction relay or its equivalent for eliminating synchronous braking is claimed in the application of D. C. Prince, Serial No. 365,762, filed March 15, 1920, assigned to the assignee of this application.

15 It will be understood that governing and speed adjusting means are provided for the turbine 1 of the arrangement shown in Fig. 6, as in the modifications heretofore described.

20 In the modifications heretofore described, I have represented the exciter as arranged to supply normal excitation to the generator and motor field windings in series and in certain modifications I have represented connections whereby overexcitation may be applied to said field windings. The modification shown in Fig. 7 involves the use of a three-wire system for exciting the field windings and such a system is particularly well adapted for carrying out my methods of 25 operation for the reason that the field windings may be readily excited either independently or together with normal or double voltage. Fig. 7 represents a system in which the operation is arranged for remote control 30 by means of a controller 60' operated by a lever 61'. The governing mechanism 21 of the turbine is arranged to be controlled by a steam lever 59' which is interlocked with the control lever 61' as hereinafter described. 35 The conventional showing of the controller segments indicates that all of the segments on the ahead and astern sides of the controller are electrically connected together. The mains of the three-wire system are represented by the lines 62', 63' and 64', the neutral 63' of which is indicated as grounded to complete the circuits supplying the windings for operating the various switches. A switch 68 is arranged to connect the motor 40 field winding 12 across lines 62' and 64' for overexcitation. A switch 69 is arranged to short circuit an adjustable resistance 65. A switch 70 is arranged to connect the motor field winding 12 across mains 62' and 63' 45 for normal excitation, and resistance 65 is provided for the purposes of adjusting this excitation to any desired value to control the power factor of the motor. A switch 71 is arranged to connect the generator field winding 2 across the mains 63' and 64' for 50 normal excitation of the generator, and switch 72 is arranged to connect the generator field winding across mains 62' and 64' for over-excitation. A switch 73 is provided 55 for enabling the transition to be made from

over-excitation to normal excitation on the generator without short circuiting one side of the three-wire system. The switches 68, 70, 71 and 72 are provided with certain interlock contacts, the function of which will be set forth in connection with the description of the operation. The electric controller lever 61' and the steam lever 59', as heretofore indicated, are interlocked in a manner to insure that the turbine speed shall be reduced during maneuvering to enable the generator and motor to get into step more readily. The steam lever 59' is provided with a cam member 74 cooperating with a pivoted locking member 75 provided with a roller 76 bearing on the cam surface. The electric controller lever 61' is provided with a member 77 provided with a plurality of notches in which the locking member 75 is arranged to engage. I have shown the member 77 as provided with three notches corresponding to the OFF, FULL SPEED AHEAD and FULL SPEED ASTERN positions of the electric controller. The cam surface of the member 74 is so arranged that the steam lever 59' must be moved approximately to the 25% speed position before the control lever 61' can be moved. It is also apparent that the parts cooperate to prevent manipulation of the steam lever 59' unless the electric control lever is in one of its three specified positions. A pivoted stop mechanism 78 having a projection 79 is arranged normally to stop the steam lever in the best maneuvering position, and this position may be found by adjusting the length of the projection 79. This stop member 78 is biased to a position in which it engages the lever 59', as shown in Fig. 8. If, however, it becomes desirable to operate at a still lower turbine speed, as for example, when it is desired to run the equipment at a very low speed in order to keep head-way or stern-way in case of a storm or for standby purposes, the latch 78 may be thrown to render the stop 79 ineffective and permit further movement of the lever 59' as shown in Fig. 9. The additional movement may be limited in any desired manner, but, as shown, the final stop is produced by the engagement of the lever 59' with the curved surface 80 of the member 78. As soon as the steam lever 59' is moved to increase the speed, stop member 78 falls back into place locating the steam lever in the maneuvering position when it is again moved to reduce the turbine speed. By this arrangement of levers and stop mechanism, the control is rendered more certain and the skill required on the part of the operator is reduced. This stop mechanism arrangement is claimed in my application, Serial No. 429,858, filed December 11, 1920, for electric ship propulsion, assigned to the assignee of this publication.

70 75 80 85 90 95 100 105 110 115 120 125 130

The operation of the modification shown

in Fig. 7 beginning with the equipment at standstill, is as follows: The turbine is set into operation in any well known manner and the steam lever 59' moved to the maneuvering position as determined by the stop mechanism 78. The control lever 61' is operated, for example, to go ahead and in passing to the first position the controller energizes controller fingers *a* and *c* to close contacts 7, 8 and 10, as in the modifications heretofore described. The first position of the controller energizes finger *p* to close switch 68. The circuit for the operating coil of switch 68 passes through interlock contact 72^b of switch 72 and interlock contact 70^a of switch 70. Overexcitation is thus impressed on motor field winding 12 which is the condition for synchronous braking. Since, however, the propeller is standing still, it is apparent that the operator will not pause in this position of the controller, but will immediately pass to the next position in which fingers *q* and *r* will be energized to close switches 72 and 73 through interlocks 71^b and 71^a, respectively, of switch 71. The closing of switch 72 applies overexcitation to the generator field winding 2 and after a delay sufficient to permit the generator field current to build up to full value, interlock contact 72^b opens, to open switch 68 to deenergize the motor field winding 12. Strong induction motor action now takes place to accelerate the propeller, and when the motor is up to speed, the operator moves the controller to the next position in which fingers *s* and *t* respectively close the circuits of the operating coils of switches 69 and 70. The circuit from controller finger *t* to the operating coil of switch 70 passes through interlock contact 68 of switch 68 which is now open. The closing of switch 69 short circuits the resistor 65 so that the closing of switch 70 impresses the full voltage of one side of the three-wire system upon the motor field winding 12 to bring the motor into synchronism with the generator. When the controller passes to its final position, contact *u* is energized to complete a circuit through interlock contact 72^a to close switch 71, to connect the generator field winding 2 across the lines 63' and 64' for normal excitation. Prior to the closing of switch 71, however, controller finger *q* is deenergized to open switch 72. Controller finger *r* is still energized, however, so that until switch 71 closes, switch 73 remains closed, so that notwithstanding the dropping out of switch 72, the connection of the generator field circuit across lines 62' and 64' is still maintained through resistance 81. This resistance is provided to prevent a short circuit across the lines 62' and 63' during the transition from overexcitation to the normal excitation on the generator. The closing of switch 71 opens interlock contact 71^a to open switch

73. Normal synchronous operation now obtains, the motor field circuit being maintained closed by switch 70 energized from controller finger *t*, and the generator field circuit being maintained closed by the switch 71 energized from controller finger *u*. Steam lever 59' may now be moved to adjust the turbine speed to any desired value. Such movement causes the locking member 75 to engage one of the notches in member 77 to prevent operation of the controller lever 61'. If it now be desired to stop or reverse the ship, it is first necessary to move the lever 59' to maneuvering position which releases the lever 61', as heretofore described. Should it be desired, while operating synchronously, to proceed at a speed lower than the speed necessary for successful maneuvering, this may be done by moving the stop mechanism 78 as heretofore set forth. In view of the description heretofore given in connection with other modifications, it is believed unnecessary to follow in detail the various circuit connections made for carrying out other maneuvering operations.

Fig. 10 represents the application of my invention to a ship propulsion system in which a plurality of propeller driving motors are arranged to drive the propellers 6 and 6'. In this arrangement the generator is represented as provided with a single stator winding 3 which is adapted to supply current to the motor stator winding 4 and 4'. The excitation circuits are represented as being arranged to supply the field windings 12 and 12' from a three-wire system with switches arranged as in Fig. 7. A disconnecting switch 82 is provided between the generator 3 and the stator windings 4 and 4'. Reversing switches 83 and 84 are provided in the circuits of the respective stator windings 4 and 4'. The arrangement of switches described permits of operating the propeller driving motors either individually or together, and makes it possible to operate one motor in one direction and the other motor in the other direction, if desired.

The modification shown in Fig. 10 is capable of being operated in the manner set forth in connection with the modifications previously described. That is to say, either or both of the motors may be connected to the generator with reversed phase rotation for synchronous braking. The arrangement of Fig. 10 permits, however, of a different mode of operation which has certain advantages. Where a motor is connected to its generator with reversed phase rotation for synchronous braking, the inductance of the generator causes a reduction of the short circuit current which decreases the braking torque to some extent. The circuit arrangement of Fig. 10 permits the propeller driving motors to be connected together independently of the generator for synchronous brak-

ing. In this way each machine works upon a machine of identical constants which gives a very effective braking torque. To secure this braking action the switch 82 will be opened and the switch 83 reversed, the switch 84 being left unreversed. The stator windings 4 and 4' are thus connected together with reversed phase rotation. Braking torque will be developed in each motor from 10 three causes: (1) passing the short circuit current through the windings of the machine generating the current; (2) passing the same current through the winding of the other machine; (3) induction motor torque by currents generated by the second machine reacting upon the rotor of the first machine. The propellers are thus quickly brought to a standstill. Switch 84 will now be reversed and switch 82 closed. The 20 excitation circuits will have been manipulated, as heretofore described, to apply over-excitation to the generator field winding, and the two propellers 6 and 6' will now be reversed and accelerated in the reverse direction.

The modification shown in Fig. 11 differs from that shown in Fig. 10 in that a plurality of generators and turbines are used. The second turbine and stator windings are represented by 1' and 3'. A reversing switch 85 is connected between stator windings 3 and 4 and a reversing switch 86 between stator windings 3' and 4'. A switch 87 is arranged to interconnect stator windings 4 and 4', and this switch is arranged to produce reversed phase rotation between these machines. The details of the excitation circuits for exciting field windings 2, 2' and 12, 12' are not shown for the reason that the 40 description heretofore given renders it obvious how these field windings may be excited in any of several different ways. In this connection, it may be noted that while a series connection is adapted to ships with 45 one motor and one generator, where two motors are supplied from a single generator the required braking torque can be developed by bucking the motors with less over-excitation in the motors.

50 The operation of the modification shown in Fig. 11 is as follows: Assuming that the ship is proceeding at full speed and that it is desired to initiate synchronous braking, switches 85 and 86 are reversed and switch 87 is closed. In this way each motor is in reversed phase rotation with respect to its generator, and the two motors are relatively in opposite phase rotation. Furthermore, the two generators are connected together 60 with opposite phase rotation. The result is that the two motors tend to stop each other, and that the generators also tend to stop each other. It is apparent that the arrangement shown in Fig. 11 may, if desired, be operated to produce synchronous

braking by merely closing switch 87, leaving switches 85 and 86 open.

The arrangement shown in Fig. 12 represents a further modification showing the propeller driving motors interconnected for synchronous braking. In this case the generator is provided with independent stator windings 88 and 89. Reversing switches 85 and 86 and cross-connecting switch 75 75 are arranged as in Fig. 11. The operation of this modification is believed to be obvious without further description.

The feature of braking by bucking the propeller driving motors is claimed in my copending application, Serial No. 500,025, filed September 12, 1921, for electric ship propulsion, assigned to the assignee of this application.

In the modifications shown in Figs. 10, 11 and 12 I have disclosed a method of stopping the propellers of a ship propulsion system by bucking the motors available where two or more motors are used. In Fig. 13 I have represented a modified arrangement of circuits which enables me to accomplish the

same result with a single motor. The generator and motor construction and line reversing contactors are as in the modifications heretofore described. The excitation circuits may be supplied in any of the ways heretofore described or their equivalents. A switch 90 is arranged to establish a single phase short circuit across the terminals of the motor stator winding 4. I have found that a greater braking effect may be produced by such a single phase circuit than can be produced by a polyphase short circuit or by reversed phase braking as heretofore described.

One way of explaining how this increased braking torque is developed is based upon the idea of resolving the armature reaction due to the single phase short circuit into two oppositely rotating components. The component of the armature reaction having the same rotation as the field member 5 corresponds to the polyphase generator function of the machine.

The component with opposite phase rotation corresponds to the field which would be produced in this machine if it were connected to another machine with opposite phase rotation thereby creating, not only losses in the primary winding, but, also, an induction motor action upon the squirrel cage winding 15 which tends to stop the machine. It will thus be seen that the generator and motor action take place simultaneously in the same machine and the three causes producing a braking torque where two motors are arranged to buck, as previously described, will be present in this internal action.

These causes as heretofore set forth are: 1, losses incurred by passing the current through the generator winding; 2, losses incident to passing the current

through the motor winding, and 3, induction motor action of one machine upon the other.

The arrangement shown in Fig. 13 is capable of being operated in a number of different ways. Single phase braking may take place without reversed phase braking by closing the single phase short circuiting switch 90 only, as heretofore set forth. The 10 method of operation will be to deenergize the field windings of motor and generator after which the line contactors will be opened and switch 90 closed. Single phase braking will then take place upon energization 15 of the motor field winding 12. When the propeller has been brought approximately to standstill, the line contactors may be closed for reversed operation and the switch 90 opened. If desired, however, the 20 single phase short circuit may be opened prior to the closing of the line contactors for reversed phase rotation. Such a method of operation, however, requires either that the speed of the ship shall have been reduced 25 to a comparatively low value or that the squirrel cage winding 15 of the motor be given especially strong reversing torque over a considerable range of slip, since, otherwise, the propeller may slip away before 30 it can be caught and reversed by induction motor action. Under some circumstances, it may be desirable to maintain the line contactors closed for reversed phase rotation, while the switch 90 is closed for 35 single phase braking. This method of braking will be especially advantageous where synchronous reversal is to be relied upon as in the modifications shown in Figs. 1 and 2, since the single phase short circuit may perform 40 the function of the polyphase short circuit of Fig. 2 in holding the propeller at standstill until the ship has reached a speed where synchronous reversal can take place.

The feature of single phase braking is 45 claimed in my application, Serial No. 500,024, filed September 12, 1921, for electric ship propulsion, heretofore referred to.

Figs. 14 and 15 disclose a particular construction of squirrel cage winding for a 50 synchronous motor of the salient pole type, which form of winding is particularly adapted for single phase synchronous braking and for securing an effective squirrel cage action for induction motor reversal. The winding comprises a high resistance 55 component consisting of a plurality of high resistance bars 91 placed near the surface of the pole pieces. Eight of these bars are shown for each pole piece. These bars 91 are connected to short circuiting end rings 92, only one of which is shown in the drawing. The low resistance component of the winding comprises a heavy copper bar 93 arranged in the center of each pole piece and 60 as near the surface of the pole as the high

resistance bars 91 will permit. In addition to this heavy bar, there is placed a heavy copper bar 94 half way between the pole pieces, and these bars 93 and 94 are connected to short circuiting end rings 95, only one 70 of which appears in the drawing. This low resistance squirrel cage winding has a high leakage reactance, first, because there are only a small number of bars and second, because of the position of the bars. At high 75 values of slip, the frequency in the induction motor secondary is high and, therefore, the leakage reactance of the copper or low resistance squirrel cage winding is high and the secondary current, therefore, flows in 80 the high resistance squirrel cage winding 91 where high losses are produced giving high induction motor torque. At low values of slip, the frequency of the secondary is 85 low, and, therefore, the leakage reactance of the low resistance squirrel cage winding is low and the secondary current flows principally in this low resistance winding. A double squirrel cage effect is thus produced.

The winding shown in Figs. 14 and 15 is 90 disclosed and claimed in my application, Serial No. 368,195, filed March 23, 1920, for double squirrel cage synchronous motors, assigned to the assignee of this application.

The double squirrel cage winding shown 95 in Figs. 14 and 15 may be employed, if desired, in all of the modifications of my invention herein described.

While my invention is peculiarly adapted to utilize the advantages of a salient pole 100 synchronous motor, it is apparent that I have disclosed features of construction and methods of operation not limited to any particular construction of synchronous motor.

I have herein shown and particularly described 105 certain embodiments of my invention and certain methods of operation embraced therein for the purpose of explaining its principle and showing its application, but it will be obvious to those skilled in the 110 art that many modifications and variations are possible, and I aim, therefore, to cover all such modifications and variations as fall within the scope of my invention which is defined in the appended claims.

What I claim as new and desire to secure by Letters Patent of the United States, is,—

1. The method of operating an electric system for ship propulsion wherein a propeller is driven by an alternating current 120 motor which comprises operating the motor as a generator to supply current to the generator for breaking the propeller from the water and bringing it approximately to standstill.

2. The method of operating an electric system for ship propulsion wherein a propeller is driven by a synchronous alternating current motor which comprises operating the motor as a synchronous generator to 130

break the propeller from the water and bring it approximately to standstill.

3. The method of operating an electric ship propulsion system comprising a synchronous generator and an alternating current propeller driving motor, adapted to be excited to operate as a synchronous machine, which comprises connecting the motor to the generator with reversed phase rotation while maintaining the motor excited to break the propeller from the water and bring it approximately to standstill.

4. The method of operating an electric ship propulsion system comprising a synchronous generator and an alternating current propeller driving motor having induction motor characteristics and adapted to be excited to operate as a synchronous machine, which comprises connecting the motor for operation as a synchronous generator to bring the propeller approximately to standstill, then operating the motor from the generator as an induction machine to reverse the propeller, and subsequently restoring the excitation to the motor for synchronous operation in the reverse direction.

5. An electric ship propulsion system comprising a synchronous propeller driving motor adapted to operate with induction motor characteristics and a synchronous generator, characterized by the fact that a controller and switches operable in response to movement thereof are arranged to introduce a time interval between the establishment of connections for exciting the field winding of said generator and a change in the connections of the field winding of said motor whereby connections may be established for operating said motor as an overexcited synchronous generator for braking purposes and for operating said generator overexcited to supply current to said motor for induction motor operation.

6. An electric system comprising a synchronous driving motor adapted to operate with induction motor characteristics, a synchronous generator, and control means including a controller and switches controlled thereby for establishing connections for operating the motor as an overexcited synchronous generator for braking purposes and for operating the generator overexcited to supply current to said motor for induction motor operation, said control means being arranged to introduce a time interval between the establishment of connections for exciting the field winding of said generator and a change in the connections of the field winding of said motor.

7. An electric system comprising a synchronous driving motor adapted to operate with induction motor characteristics, a synchronous generator, and means whereby connections may be established for operating said motor as a synchronous generator for

braking purposes, as an induction motor supplied from said synchronous generator, and as a synchronous motor supplied from said synchronous generator, said means comprising connections arranged to be operated to excite the motor and generator individually for braking and induction motor operation respectively, and means arranged to provide a time interval between the establishment of the connections for exciting one of said field windings and a change in the connections of the other field winding.

8. An electric system comprising a synchronous driving motor adapted to operate with induction motor characteristics, a synchronous generator, means whereby connections may be established for operating said motor as a synchronous generator for braking purposes, as an induction motor supplied from said synchronous generator, and as a synchronous motor supplied from said synchronous generator, and means arranged to control the transition from one of said connections to another in accordance with conditions of the system which determine the fact that the system may function properly when the changed connections are established.

9. An electric ship propulsion system comprising a synchronous generator, a synchronous motor adapted to operate with induction motor characteristics and arranged to drive a propeller, means adapted to be operated to establish connections whereby the motor may be operated as a synchronous generator for braking purposes and to establish connections whereby the motor may be operated as an induction motor supplied from said generator, and means connected to be responsive to the frequency of said braking currents arranged to control the establishment of induction motor connections.

10. An electric ship propulsion system comprising a synchronous generator, a synchronous motor adapted to operate with induction motor characteristics and arranged to drive a propeller, means adapted to be operated to establish connections whereby the motor may be operated as an induction motor supplied from said generator and to establish connections whereby the motor may be operated as a synchronous motor supplied from said generator, and means connected to be responsive to some quantity whose variation is a function of the power supplied to the motor, while operating as an induction motor, arranged to control the establishment of synchronous motor connections.

11. An electric ship propulsion system comprising a synchronous generator, a synchronous motor adapted to operate with induction motor characteristics and arranged to drive a propeller, means adapted to be

- operated to establish connections whereby the motor may be operated as an induction motor supplied from said generator and to establish connections whereby the motor 5 may be operated as a synchronous motor supplied from said generator, and means responsive to the frequency induced in the field winding of said motor, while operating as an induction motor, arranged to control 10 the establishment of synchronous motor connections.
12. An electric ship propulsion system comprising a synchronous generator, a synchronous motor adapted to operate with 15 induction motor characteristics and arranged to drive a propeller, means adapted to be operated to establish connections whereby the motor may be operated as a synchronous generator for braking purposes, to establish connections whereby the motor may be operated as an induction motor supplied from said generator, and to establish connections whereby the motor may be operated as a synchronous motor supplied from said generator, means connected to be responsive to the frequency of said braking currents to control the establishment of induction motor connections, and means connected to operate in accordance with slip frequency to control the establishment of 50 synchronous motor connections.
14. An electric ship propulsion system comprising a polyphase synchronous propeller driving motor provided with a relatively high resistance low reactance winding of the squirrel cage type, and a relatively low resistance high reactance squirrel cage winding, a polyphase synchronous generator for driving said motor, and means comprising controller and switches 55 controlled thereby whereby connections may be established for operating said motor as an induction motor supplied from said synchronous generator for maneuvering purposes and for operating said motor as a synchronous motor supplied from said synchronous generator for normal navigation, said means being arranged to introduce a time interval between the establishment of connections for exciting the field 60 winding of said generator and a change in the connections of the field winding of said motor.
13. An electric ship propulsion system comprising a synchronous generator, a synchronous motor adapted to operate with induction motor characteristics and arranged 65 to drive a propeller, means adapted to be operated to establish connections whereby the motor may be operated as a synchro-

In witness whereof, I have hereunto set my hand this 14th day of February, 1920.

ERNST F. W. ALEXANDERSON.
